C. D. HIBBS.
TUBE VULCANIZER.
APPLICATION FILED OCT. 22, 1915.

1,198,224.

Patented Sept. 12, 1916

UNITED STATES PATENT OFFICE.

CASSELL D. HIBBS, OF FORT WORTH, TEXAS.

TUBE-VULCANIZER.

1,198,224.

Specification of Letters Patent. Patented Sept. 12, 1916.

Application filed October 22, 1915. Serial No. 57,351.

To all whom it may concern:

Be it known that I, CASSELL D. HIBBS, a citizen of the United States, residing at Fort Worth, in the county of Tarrant and State of Texas, have invented certain new and useful Improvements in Tube-Vulcanizers, of which the following is a specification.

My invention relates to vulcanizers, and more particularly to vulcanizers for repairing inflatable tires; and the object is to provide a device which is simple in construction and convenient for operating on tubes of rubber for tires and other articles and which is strong and durable and simple in operation.

Another object is to provide a plurality of pressure plates all adapted to rest against a tube plate and to provide means for keeping the tube plate constantly hot.

Another object is to provide ready means for drying the articles prior to vulcanizing.

Other objects and advantages will be fully explained in the following description and the invention will be more particularly pointed out in the claims.

Reference is had to the accompanying drawings which form a part of this application.

Figure 1 is a front elevation of the machine. Fig. 2 is a broken sectional view, taken substantially on the line $\alpha-\alpha$ of Fig. 1. Fig. 3 is a detail view of the adjustable weight. Fig. 4 is a perspective view of one of the pressure pads. Fig. 5 is a vertical cross-section of the same, taken on the line $y-y$ of Fig. 4. Fig. 6 is a broken view, illustrating the use of a spring instead of a weight for controlling the pressure pads.

Similar characters of reference are used to indicate the same parts throughout the several views.

The machine is provided with uprights 1 and 2 which can be sufficiently braced by the rod or shaft 3 and the tube plate 4 and the rest bar 5. The rods 3 and 5 may be provided with lock nuts 6 for holding the frame rigid. The tube plate 4 is mounted rigidly in the frame pieces 1 and 2 and is set on one corner to make the condensation of steam collect at a point below the application of the pressure pads so that the condensation will not interfere with the proper curing of the rubber. Provision may be made for draining the condensation, as by a drain cock 7. The tube plate may be supplied with steam through a pipe 8. The

upper side of the tube plate 4 is made concave to receive the compressed air pipe 9 which receives compressed air from some supply source through a pipe 10 which is provided with a cock. The air in the tube 9 will be heated by the hot steam in the tube plate 4 and is used for drying cement, as will be further detailed later. The bottom of the tube plate forms the pressure and heating surface against which the rubber tubes are pressed for curing.

A plurality of pressure pads are provided and these pads may be of different sizes, as the pads 12 and 13. Each pad is made of a metal frame 14 and asbestos plates 15 and 16. The plate 15 is bolted to the metal plate 14 and the plate 16 is attached to the plate 15 by cement or other plastic attaching material. The plates 15 and 16 may be asbestos, cloth, rubber, or any suitable material that will not mar the inner tube. The plate 14 has depending ears 17 for attachment to a lever 18, a lever being provided for each pad. The levers 18 are fulcrumed on the shaft or rod 3 and the lower arm of each lever is provided with a pedal 19 in convenient reach of the foot of the operator. There is an advantage in having the axis or fulcrum of the levers between the operating weight or spring and pressure pad. An adjustable weight 20 is mounted on an arm 21 which is integral with the lever 18, a weight being provided for each lever. The weights press the pads 12 or 13 against the rubber to be vulcanized. A substitute for each weight may be a spring 22 which is connected to the arm 21 and to a bar 23 extending across the machine. When the operator puts his foot on a pedal 19 and presses down, the lever 18 will stop against the rest bar 5 and remain there while the operator adjusts the rubber tube on the pad. In operation, the operator can attend to a number of pads and have a number of rubber tubes curing at the same time.

Another advantage of the machine is the provision for drying the cement which is used in closing the cavities. The rubber cement is dried by hot air. A hose 24 is connected with the compressed air pipe 9, which contains heated compressed air, receiving its heat from the tube plate 4. The hose 24 is provided with an air cock or other device 25 for convenience in turning on and cutting off the hot air. When an article is to be dried the pipe 24 is directed

to the article and the cocks 25 opened. The compressed air is ready to dry whatever article is necessary.

The triple armed lever 18 provides for 5 quick action in locating the pad and for placing the article to be treated on the tube plate to be pressed by the pad. The lever is operated by the foot and the rest 3 is provided so that the foot can hold the lever 10 stationary while the article to be treated is located. When the article is located, the foot is removed and pressure is applied automatically. The spring will operate in the same manner. The tube plate 4 is kept 15 hot by steam and is always ready for action at any point thereon.

Various changes may be made in the construction of the several parts without departing from my invention. The number 20 of pads may be increased or decreased. The pads may be manipulated by hand as well as by the foot by using the handle 26.

The machine herein described is capable 25 of general application for vulcanizing rubber tubes and various other rubber articles which can be cured on a flat plate, such as rubber bags and rubber boots.

What I claim, is,—

1. A tube vulcanizing device comprising 30 a frame, a tube plate mounted at an angle in said frame, a plurality of pressure pads, a shaft mounted in said frame, a triple armed lever for each pad fulcrumed on said shaft, means carried by each lever for pressing 35 the pad carried thereby against said plate, and means for containing a heating element in said plate.

2. A tube vulcanizing device comprising 35 a frame, a tube plate set at an angle in said frame, a plurality of pressure pads, a shaft mounted in said frame, a lever for each pad mounted on said shaft and having one arm 40 for pressing the pad against said plate, one arm carrying means for controlling the last mentioned arm, and a pedal arm for 45 operating said lever for holding the pad away from said plate, and means for containing a heating element in said plate.

3. A tube vulcanizing device comprising 50 a frame, a tube plate set at an angle in said frame, a plurality of pressure pads, a shaft mounted in said frame, a triple armed lever for each pad fulcrumed on said shaft, a rest 55 bar for said levers, means carried by each lever for holding the pad against said plate, and means for containing a heating element in said plate.

4. A tube vulcanizing device comprising 60 a frame, a tube plate set at an angle in said frame and having a steam chamber therein, 65 means for draining condensation therefrom, means for maintaining hot steam therein, a plurality of pressure pads, a shaft mounted in said frame, and a triple armed lever for each pad fulcrumed on said shaft.

5. A tube vulcanizing device comprising 65 a frame, a tube plate having a steam chamber therein mounted in said frame, a plurality of pressure pads for receiving and pressing articles to be vulcanized against 70 said plate, a shaft mounted in said frame, a lever for each pad fulcrumed on said shaft having one arm for carrying the pad, one arm for exerting pressure on the pad, and one operating arm, and a rest bar for said 75 levers.

6. A tube vulcanizing device comprising 80 a frame, a tube plate having a steam chamber therein mounted in said frame, a plurality of pads for receiving and holding 85 articles to be vulcanized, a lever for each pad for operating the pad, and means in connection with said plate for drying the articles to be vulcanized on said plate.

7. A vulcanizing device comprising a 85 frame, a tube plate having a chamber for hot steam mounted in said frame, a plurality of pressure pads, a shaft in said frame, a pad controlling lever for each pad fulcrumed on said shaft, and a compressed air 90 pipe heated by said plate for drying articles prior to being vulcanized on said plate.

In testimony whereof, I set my hand this 16th day of October, 1915.

CASSELL D. HIBBS.
